UNITED STATES PATENT OFFICE.

RICHARD B. DAVIS, OF LOS ANGELES, CALIFORNIA, ASSIGNOR OF ONE-HALF TO WILLIAM K. MASON, OF CALIENTE, NEVADA.

RAILWAY SIGNAL SYSTEM.

No. 911,118.

Specification of Letters Patent.

Patented Feb. 2, 1909.

Application filed November 8, 1907. Serial No. 401,207.

To all whom it may concern:

Be it known that I, RICHARD B. DAVIS, a citizen of the United States, residing at Los Angeles, in the county of Los Angeles, State 5 of California, have invented new and useful Improvements in Railway Signal Systems, of which the following is a specification.

My invention relates to a railway signal system designed to take the place of the 10 usual air signal system whereby the signal whistle in the locomotive cab may be blown from any point on the train.

An object of my invention is to provide a 15 quick acting electrically operated valve for the whistle which will blow the whistle immediately upon the operation of a signal switch, and will quickly resume its normal position upon the release of the switch so that successive blasts of the whistle may follow 20 low each other quickly.

A further object is to provide a system 25 which may be easily put on a car not permanently equipped with the same so that the signal whistle may be blown from any point on the train.

I accomplish these objects by means of the device described herein and illustrated in the accompanying drawings in which:—

Figure 1,—is a fragmentary view of a train 30 showing diagrammatically the disposition of the different parts of the apparatus for my system thereon and the electric connecting cables therefor. Fig. 2,—is a central vertical section of the whistle valve. Fig. 3,—is a 35 diagrammatic detail of one of the car switches. Fig. 4,—is a diagrammatic detail of one of the car push buttons and the connections therefor; Figs. 2 and 4 combined illustrating diagrammatically the electrical 40 operation of the system. Fig. 5,—is a perspective detail partly in section of a hose coupling between adjacent cars showing diagrammatically the passage of the connecting wires through the same. Fig. 6,—is a view 45 similar to a portion of Fig. 1 showing a modified form of connection between the cars for connecting a car not equipped with my system to a car equipped with the same. Fig. 7,—is a perspective view of the connecting 50 cord and fixtures used to temporarily provide a car with my system. Fig. 8,—is an enlarged detail of the end of an equipped car showing diagrammatically the connections for connecting an equipped car to an un- 55 equipped car.

Referring to the drawings, and more particularly to Fig. 1, 10 designates a locomotive provided with a tender 11. Immediately behind tender 11 a baggage car 12 is illustrated, the drawing of the same being broken 60 off in the upper part of Fig. 1 and continued in the lower part thereof. Behind the baggage car the front end of a passenger car 13 is illustrated.

Located in cab 14 of locomotive 10 is a 65 whistle valve 15 connected by pipe 16 to main reservoir 17 of the locomotive. Wires 18 lead from whistle valve 15 and a battery 19 is connected in circuit with one of the wires, this battery furnishing the necessary current 70 for the operation of the whistle valve. Wires 18 are then run together in a cord 20 which passes rearwardly along the train, connecting between cars on the air brake hose couplings and running up into the baggage car as shown in Fig. 1. Passing rearwardly from the baggage car cable 20 passes into passenger car 13 and through the same, this construction being repeated for every car in the train. Located in the baggage car 80 over desk 21 and in the passenger car at suitable intervals are pendent push buttons 22 which are adapted by their operation to close the circuit between wires 18 and thereby operate whistle valve 15 to blow the whistle. 85 Also connected with cable 20 in the passenger car is a switch 23 adapted to be operated by a cord 24 which traverses the length of the passenger car, taking the place of the usual air signal cord.

The whistle valve will first be described in detail. Wires 18 connect with a horse shoe electro-magnet 25 mounted on an adjustable inverted U shaped frame 26 which is secured to a base plate 27. A casing 27' covers the 90 magnet and affords it protection from any accidental injury. Mounted in screw threaded engagement in a circular boss 34 on base plate 27 is a vertical cylinder 28 extending downwardly from the base plate and carrying a spring supporting cap 29 on its lower end. A screw threaded plug 30 which closes the upper end of cylinder 28 is provided with a central vertical bore 31 adapted to receive a vertically movable valve rod 32 which carries 95 on its upper end a circular armature 33 for magnet 25. Boss 34 which surrounds cylinder 28 is provided with an air inlet 35 in which air pipe 16 leading from main reservoir 17 is adapted to be screwed. A circular port 36

leads around cylinder 28 and communicates with inlet 35. Plug 30 is also provided with a circular port 37 around valve rod 32 which communicates with port 36 by means of bore 38 so that the air fed into circular port 36 immediately passes into port 37. Rod 32 is provided with a longitudinal port 39 consisting of a circular groove which extends for some distance along its length and is normally in the relative position shown in Fig. 2. Loosely surrounding rod 32 and fitting closely in the bore of cylinder 28 is a piston 40 which is supported in the position illustrated by a spiral spring 41 resting at its lower end on cap 29. Rod 32 is reduced in diameter at its lower end as at 42 and is provided with a coiled spring 43 surrounding the reduced portion, the spring being held between a slidable washer 44 bearing against shoulder 45 and adjusting nut 46 on the lower end of rod 32.

In the operation of the whistle valve the circuit through battery 19 and electro-magnet 25 is closed by means of any of the switches 25 in circuit with wires 18 and the magnets are thereby energized to attract armature 33 which rises, carrying valve rod 32 with it. Ports 39 are thereby brought into register with port 37 and air is admitted into them to 30 pass downwardly into a cup shaped depression 47 in the upper end of cylinder 40. Piston 40 is thereby forced downwardly against the pressure of spring 41 until the upper edge of the piston uncovers a circular port 48 in cylinder 28 which leads to an outlet opening 49 in which whistle 50 is mounted. During this passage the bottom of piston 40 strikes washer 44 and spring 43 is thereby compressed, providing magnet 25 has not yet 35 been deenergized. If the magnet has been deenergized rod 32 is forced downwardly into its normal position as illustrated and the supply of air to the space above piston 40 is thereby cut off. Enough air has entered the 40 space above the piston to blow whistle 50 for an appreciable period of time, piston 40 gradually moving upwardly as the air above it passes out through the whistle. After the top of the piston passes port 48 the air above the 45 piston quickly leaks out between the piston and rod 32 through a leak port 32' out in rod 32 so that the piston resumes its normal position. This leak port is of such a length that the 50 passage therethrough is cut off when the piston is in its lower position and open when in its upper position as shown. In case the magnet is energized for a longer period of time than is consumed in the passage of piston 40 downwardly, the whistle is blown until the magnet is deenergized and armature 33 is forced downwardly by the action of spring 43 which piston 40 compresses on its downward movement. Piston 40 then moves upwardly as before and cuts off the supply 55 of air to the whistle.

By means of the above described whistle valve it will be seen that the whistle will be operated by even an instantaneous closure of the electrical circuit through the magnet. Closure means for the circuit of wires 18 are provided in each of the cars and comprise in the majority of cases a pendent push button 22 which is connected by wires 56 across wires 18, the individual push buttons being all in multiple with each other. Wires 56 are preferably formed into cords 57 which support push button 22 from cord 20 which passes through the cars. Another form of closure for the circuit is shown in diagrammatic detail in Fig. 3 and consists of a switch 23 provided with two contacts 58 connected by wires 59 to wires 18 of cord 20. These contacts are also connected across wires 18 and in multiple with push button 22. A pivoted arm 60 normally held in the position illustrated by a spring 61, is adapted to connect with contact 58 and form a connection between the same upon a pull being exerted on cord 24 which passes through the car as before stated. Thus, upon the closure of any of the push buttons or the switch just described, the whistle valve will be operated to blow the whistle for a length of time which the period of closure of the circuit determines. If a signal of a plurality of blasts is used the successive closures of the circuit may follow closely on each other as the valve resumes its normal position very quickly and thereby cuts off the supply of air to the whistle.

In Fig. 5 I have illustrated a method of connecting the wires of cord 20 between the cars which consists in forming suitable contacts on the hose couplings so that when the air brake hose is coupled up the electrical connections are automatically made. To this end wires 18 are wound around the air brake hose 76 in the walls thereof as shown in Fig. 5 and are passed through coupling fixture 70, one of the wires being connected to contact plate 71 while the other is connected to contact plate 72 set in the face of the coupling as illustrated. These contact plates are insulated from the metallic body of the coupling fixture and are adapted to contact with a corresponding set of plates 73 and 74 on coupling fixtures 75 which is an exact counterpart of fixture 70. Wires 18 on the other side of the coupling connect with plates 73 and 74 and lead out through the coupling to run through hose 77 which leads to the next car. By means of thus making connections between adjacent cars the extra trouble and labor of making a separate connection for the signal system is done away with and the signal system is automatically connected up at the same time that the air system is connected. In Fig. 6 I have illustrated the method of connecting a car equipped with my system to a car not so equipped. To this end the

front and rear ends of every car equipped with my system are provided with sockets 80 which are connected to wires 18 by branch wires 81, these sockets being connected across wires 18 just as the different switches are connected across these wires.

- 5 In Fig. 7 I have illustrated a form of portable cord by which a car not equipped with my system may be quickly and efficiently equipped with the same. A cord 10 82 is provided which carries two wires 83 corresponding to wires 18 as before explained. This cord 82 is long enough to reach completely through a car from end to end and 15 is provided with a plug 84 on one end and a socket 85 on the other. Plug 84 is connected to wires 83 and is adapted to be inserted in socket 80 so as to form an electrical connection between wires 81 and wires 83. 20 The cord is carried through the car, having pendent cords 86 carrying wires 87 which connect with push buttons 88 of a construction similar to the one before described, and by an operation of any of these push buttons 25 the circuit across wires 83 will be closed thereby operating the signal whistle in the manner described. As before stated one end of cord 82 is provided with a socket 85 which is adapted to connect with the plug 84 of an 30 adjacent car if that car is also provided with a similar temporary cord. In case the adjacent car is one provided with my system a double ended plug 89 is inserted in socket 85 which plug is adapted to fit into a socket 35 80 on the adjacent car.

From the foregoing description it will be observed that I have provided a system which efficiently replaces the usual air signal system of railway trains and which in every 40 particular operates more efficiently than the air system. This efficiency is especially noted in the speed of action of the system, it not being necessary to pause between successive closures of the circuit in order to 45 allow the signal valve to return to its normal position. This speed of action is mainly effected by means of the electrical operation of the valve as the valve is instantly moved on a closure of the circuit instead of being 50 operated after an elapse of time for a slow reduction in the train line pressure as is usually the case.

Having described my invention what I claim as new and desire to secure by Letters 55 Patent is:—

1. A train signal, comprising a pair of electrical conductors passing through the cars of a train; means in the cars to close the circuit between said conductors; a source of electrical energy interposed in the circuit of said

wires; and electro-magnetic means for operating a pneumatic signal, comprising a cylinder; a resiliently supported piston in said cylinder; an electro-magnet and movable armature therefor; a slide valve connected 65 to said armature and adapted to admit air to said cylinder above said piston, said cylinder being provided with a port connecting with the pneumatic signal, said port adapted to be uncovered by the movement of said piston. 70

2. In a train signal, electro-magnetic means for operating a pneumatic signal, comprising a frame; an armature movably mounted on said frame; electro-magnetic means for moving said armature; a fluid 75 pressure controlling valve connected to said armature; a cylinder; and a piston in said cylinder adapted to be moved by fluid pressure from said valve, said cylinder being provided with a signal port adapted to be uncovered by the movement of said piston. 80

3. In a device of the class described, electro-magnetic means for operating a pneumatic signal comprising a frame; an electro-magnet mounted in said frame; a cylinder 85 mounted on said frame; a spring supported piston in said cylinder; an armature for said magnet movably mounted in said frame; and a slide valve connected to said armature and adapted to admit air to said cylinder above 90 said piston upon the energization of said magnet, said cylinder being provided with a port below the upper face of said piston connecting with the pneumatic signal.

4. A fluid pressure signal operating means, 95 comprising a cylinder having an outlet port in one of its walls, a piston in said cylinder adapted to uncover said port by its movement, a valve adapted to admit fluid pressure to said cylinder and electro-magnetic 100 means to operate said valve.

5. A train signal, comprising an electrical circuit passing through the cars of a train, means in the cars to close said circuit, a source of electrical energy in said circuit, and 105 electro-magnetic means in said circuit to operate a fluid pressure signal, comprising a cylinder having a signal port in its wall, a piston in said cylinder adapted to uncover said port by its movement, a valve to admit 110 fluid pressure to said cylinder, and electro-magnetic means to operate said valve.

In witness that I claim the foregoing I have hereunto subscribed my name this 28th day of October, 1907.

RICHARD B. DAVIS.
